NONREMOVABLE CLOSURE CAP

Martinello Patrick Dougherty, Marysville, Kans.

Application November 14, 1938, Serial No. 240,225

13 Claims. (Cl. 221—60)

This invention has to do with a closure device for the end of a conduit or the like and relates particularly to a cap that is provided with means preventing its disassociation from the conduit 5 when in non-closing relation therewith. That is, the embodiment of the invention herein referred to is non-removable in the sense that it is operable to expose the end of a stem, tube or other conduit with which it is associated without complete detachment of the parts.

An object of the present invention is the provision of a non-removable cap of unitary structure which completely clears the open end of a stem or spout when manipulated for permitting 15 ingress or egress of material into or from the open end thereof.

Another object of the present invention is the provision of a non-removable cap as the above which is readily assembled with the part that it 20 is to close.

Still another object of the present invention is the provision of a non-removable cap of the above character that is easily and economically manufactured.

25 A further object of the invention is the provision of an expediently manipulatable non-removable cap composed of neatly arranged elements giving a decided sales dress to articles of merchandise to which it is attached.

30 Other desirable objects of my invention will become apparent while reading the following description with reference to the single sheet of drawing constituting a part of this application, and wherein:

35 Fig. 1 is a fragmentary side elevational view of a collapsible tube having upon the discharge stem thereof a closure device embodying the preferred form of the invention;

Fig. 2 is a view partly in cross section taken on 40 the line 2—2 of Fig. 1;

Fig. 3 is a view illustrating the device in the open position for permitting discharge of tube 45 contents through the stem; and

Fig. 4 is a perspective view showing the interior 50 of the device illustrated in the preceding figures.

Fig. 5 is a view similar to Fig. 3, showing a modified form of device with parts broken away for clarity.

The same reference characters where appearing 55 in various figures of the drawing and throughout the following description designate the same respective structural parts.

Although the invention is here described as it may be applied to the stem of a collapsible tube, 60 it will be readily apparent that this specific em-

bodiment is illustrative only. Other embodiments are adaptable for different uses. For example, non-removable caps made in accordance with the teaching of the present disclosure may be used for closing the ends of gas or water pipes, valve stems 5 for inflated vehicle tires or conduits of any nature whatsoever.

Referring now to the drawing, and particularly to Figs. 1, 2 and 3, there will be seen one end of a collapsible tube 10 similar to those commonly 10 used for packaging toilet pastes and creams. Said tube 10 has a discharge stem 11 provided with a threaded section 12 and a shank 13 of reduced diameter.

The closure device 14 disposed upon the stem 15 15 11 comprises a cap 15 having an end wall 16 and a skirt 17. Said skirt has a comparatively large opening 18 in one side and a notch-like opening 19 in the substantially diametrically opposite side thereof. The cap 15 is internally threaded as indicated at 20 and the lower side of the skirt is internally threaded as indicated at 21.

In Figs. 1 and 2 it can be seen that the threaded section 12 is tapered, the diameter at the tip of the stem being less than at that portion adjacent 25 to the shank 13. The threaded section 21 in the skirt 17 is of such diameter and pitch as to fit that part of the threaded section 12 near shank 13. Such threaded section 21 extends in excess of 180 degrees about the interior of the skirt 17 30 to enable it to embracingly grip the threaded section 12. Threaded section 20 in the cap 15 is of the proper diameter and pitch for cooperating with the threaded section 12 near the stem tip. That portion of the skirt between the threaded 35 lower end and the cap 15 has ample internal diameter for clearing threaded section 12 as is plainly shown in Fig. 2.

Although the closure device is hereinabove described as comprising a cap 15 provided with an 40 apertured and notched skirt 17, said device may be described with equal appropriateness by referring to the lower internally threaded part 22 of the skirt as a gap ring or discontinuous retaining means, and by referring to the parts at the opposite sides of the opening 18 as bridge members 45 for interconnecting the ring and cap.

Assembly of the device 14 with the stem 11 is accomplished by turning the threaded section 21 onto and beyond the threaded section 12. The 50 cap is thereafter screwable into closing relation on the threaded stem tip while the threads in the lower end of the skirt are advanced idly along the stem shank.

Access to contents of the tube 10 is provided 55

for by unscrewing the cap from the stem tip and thereafter tilting the device 14 in the manner illustrated in Fig. 3, the tip of the stem being thus projected through the opening 18 while the 5 notch or open space 19 receives a section of the stem shank. Rounded corners 23 are provided at the lower end of said notch to facilitate the tilting manipulation of the device. Threaded sections 12 and 21 constitute stop means preventing inadvertent displacement of the device 10 endwise from the stem 11. It will be observed that while the device is thus adjusted, no part thereof coincides with the path taken by the material extruded from the tube. Consequently 15 the device avoids becoming soiled and untidy in appearance, and the cap 15 does not become filled or clogged with an undesirable cake of the tube contents.

The device may be made of Bakelite, Celluloid 20 or other conventional materials and the skirt 17 may be resilient so that when the device is turned in the manner indicated in Fig. 3, or further as illustrated by the modified device 14' shown in Fig. 5, the sections at the opposite side 25 of the notch 19 will grippingly engage the stem to yieldingly retain the device in the tilted position. When it is again desired to close the end of the stem the device will be returned coaxially with the stem preparatory to turning the cap 15 30 upon the tip portion of the threads 12.

The modified form of device 14' shown in Fig. 5 embodies for the most part the same elements as the device shown in the lower numbered figures, and the corresponding elements are identified by the same reference numerals with a prime added. This second form of the invention has lateral arcuately shaped edges 50 at the sides of the notch 19'. The retaining means on this second form of the invention comprises a rib 51 35 which is slidable past the bead 52 on the shank of stem 11' when the device is forced endwise onto said stem incident to expanding the resilient skirt 17'. After the rib 51 is forced past the bead 52 the skirt contracts, snapping the device 40 in non-removable relation upon the stem or conduit 11'.

The device in Fig. 5 is manipulative like the first described device, but when in the open position, as illustrated, the arcuate edges 50 serve 50 to maintain such open position. That is, when the device is tilted to its fully opened position it wedges into place with the edges 50 bearing against the end of tube 10' while the sides of the opening 18' bear against the bead 52.

55 While my invention has been shown and described in its preferred forms, other embodiments may be made without departing from the spirit of the invention, the scope of which is in nowise intended to be limited except as defined in the 60 appended claims.

I claim:

1. In a non-removable closure device for a conduit or the like having a threaded end section and a neck of less diameter adjacent thereto, an internally threaded cap turnable onto said threaded section for closing the end of said conduit, an internally threaded gap ring spaced axially from and in opposed relation with the open end of said cap, and a bridge section connecting said cap and said ring in a manner to leave a space between the cap and ring, said ring being turnable onto and advanceable beyond the conduit threaded section into registry with said neck while the cap is threaded onto said 75 threaded section, said ring being retractable

while remaining in registry with a part of said neck pursuant to removal of said cap, and said device following such removal of the cap being tilttable incident to said space between the cap and ring receiving the end of said conduit and the ring gap receiving a portion of said conduit neck.

2. In combination, a spout, a closure device upon said spout comprising a cap and a skirt extending axially from the open end of said cap, 10 said skirt having an aperture in one side and a notch in the substantially opposite side thereof, stop means permitting mounting of said device with the skirt upon and about the spout and adapted to prevent accidental displacement of 15 said device from said spout, means for securing the thus mounted device in position for holding the cap in closing relation with the end of said spout, and said device while upon the spout and with the cap out of closing relation therewith 20 being tilttable to receive a section of the spout in the skirt notch incident to placing the skirt aperture in registry with the end of the spout.

3. In combination, an open ended conduit, a closure device upon said conduit comprising a 25 cap for closing the end of said conduit, discontinuous retaining means disposed about said conduit in opposed spaced relation with the open end of said cap and bridge parts connecting said cap and retaining means, said bridge parts being 30 spaced apart to leave openings in substantially opposite sides of said device, stop means permitting mounting of said device with the retaining means about a section of the conduit and cooperatively abuttable with said retaining means 35 to prevent displacement of the device endwise from the conduit, means for securing the thus mounted device in position for holding the cap in closing relation with the end of the conduit, and said device while upon the conduit and with the cap out of closing relation therewith being 40 tilttable to receive a side section of the conduit between adjacent portions of the discontinuous retaining means and in one of the side openings of the device and to receive the end of said conduit in the opposite of said side openings. 45

4. In combination, an open ended conduit, a closure device upon said conduit comprising a cap for closing the end of said conduit and a skirt depending from the open end of said cap, 50 said skirt having an aperture in one side and a notch in substantially the opposite side thereof, cooperative thread means on said device and said conduit meshable for permitting said device to be turned onto the conduit, said thread means being of limited extent and capable of being run through after predetermined turning of the device whereupon said device is advanceable further onto the conduit independently of said thread means but is limited by said thread means in simple retractive movement, and additional cooperative thread means on said device and conduit, the additional thread means being meshable upon such further advance of the device and thereupon operable by additional turning of the device to draw the cap into closing relation with the end of the conduit, and said device while between the positions for mesh of either of said thread means being tilttable to receive a side section of the conduit in said skirt 60 notch incident to placing the skirt aperture in registry with the end of said conduit. 65

5. In combination, an open ended conduit, a closure device upon said conduit comprising a cap for closing the end of said conduit, discon- 70

- tinuous retaining means disposed about said conduit in opposed spaced relation with the open end of said cap and bridge parts connecting said cap and said retaining means, said bridge parts being spaced apart to leave openings in substantially opposite sides of said device, cooperative thread means interiorly of said device and exteriorly of said conduit meshable for permitting said device to be turned onto said conduit, said thread means being of limited extent and therefore capable of being run through after predetermined turning of the device whereupon said device is advanceable further onto the conduit independently of said thread means but is limited by said thread means in simple retractive movement axially of the conduit, and additional cooperative thread means interiorly of said device and exteriorly of said conduit, the additional thread means being meshable upon such further advance of the device and thereupon operable by additional turning of the device to draw the cap into closing relation with the end of the conduit, and said device while between the positions for mesh of either of said thread means being tiltable to receive a side section of the conduit in one of the side openings of said device incident to receiving the end of the conduit in the other of said side openings.
6. A closure device comprising a cap, an internally threaded discontinuous retaining ring in opposed spaced relation with the open end of said cap, and a bridge connecting and maintaining such relation of said cap and retaining means, said bridge providing a space registering with and forming a continuation of a breach in said ring, and said connecting means also providing additional space at substantially the diametrically opposite side of the device.
7. A closure device comprising a cap, an internally threaded discontinuous retaining ring in opposed spaced relation with the open end of said cap, and bridge members interconnecting the cap and ring to secure them in such relation, said bridge members being spaced apart to provide an opening at one side of the device in communication with a breach in the ring and also to provide an opening at substantially the diametrically opposite side of the device.
8. A closure device comprising a cap, an internally threaded discontinuous retaining ring in opposed spaced relation with the open end of said cap, and an apertured bridge member interconnecting the cap and ring to secure them in such relation, said bridge member being disposed substantially diametrically oppositely of the device with respect to a breach in said ring.
9. A closure device comprising an internally threaded cap, an internally threaded discontinuous retaining ring in opposed spaced relation with the open end of said cap, the diameter of the threads in the ring exceeding that of the threads in the cap, and bridge members interconnecting the cap and ring to secure them in such relation, said bridge members being spaced apart to provide an opening at one side of the device in communication with a breach in the ring and also to provide an opening at substantially the diametrically opposite side of the device.
10. A closure device comprising a cap, a discontinuous expansible retaining ring in opposed spaced relation with the open end of said cap, and resilient bridge members interconnecting the cap and ring to secure them in such relation, said bridge members being spaced apart to provide an opening at one side of the device in communication with a breach in the ring and also to provide an opening at substantially the diametrically opposite side of the device.
11. A closure device comprising a cap, a discontinuous retaining ring in opposed spaced relation with the open end of said cap and having stop means thereon, and bridge members interconnecting the cap and ring to secure them in such relation, said bridge members being spaced apart to provide an opening at one side of the device in communication with a breach in the ring and also to provide an opening at substantially the diametrically opposite side of the device, and said bridge members having curved cam sections thereon projecting outwardly from the device at the sides of the first of said openings.
12. In combination, an open ended conduit having stop members spaced axially thereof, a closure device upon said conduit comprising a cap for closing the end of said conduit, discontinuous retaining means disposed about said conduit between said stop members in opposed spaced relation with the open end of said cap, and wedge-like bridge parts connecting said cap and retaining means, said bridge parts being spaced apart to leave openings in substantially opposite sides of said device, said device being tiltable into position to receive a side section of the conduit between adjacent portions of the discontinuous retaining means and in one of the side openings of the device and to receive the end of said conduit in the opposite of said side openings, and said bridge members being of such dimensions as to releasably wedge between said stop members when the device is in such tilted position.
13. A closure device comprising a cap, a discontinuous retaining ring in opposed spaced relation with the open end of said cap, and a bridge connecting and maintaining such relation of said cap and retaining means, said bridge providing a space registering with and forming a continuation of a breach in said ring, and said connecting bridge also providing additional space at substantially the diametrically opposite side of the device.

MARTINELLO PATRICK DOUGHERTY. 60
